HINGE

Grady A. Loftin and Laurence K. Loftin, Alta-vista, Va., assignors to The Lane Company, Inc., Altavista, Va., a corporation of Virginia

Application June 22, 1936, Serial No. 86,652

10 Claims. (Cl. 16—142)

This invention relates to a hinge and is particularly directed to a combined hinge and support especially adapted for use on the lids of chests and the like articles.

5 The invention is particularly advantageous for use on chests and the like articles which are constructed of or lined with cedar or similar aroma-emitting material. In order to maintain such chests in a substantially aroma-tight condition so as to ensure the effectiveness of the chest in the killing of moths and similar insects it has been found necessary to provide the chests with various features designed to retain within the chest the aroma given off by the cedar material. A particularly suitable means for this purpose is the provision of resilient strip material between the lid and the top of the body in such a position that when the lid is fully closed the resilient strip material is under a 10 substantial compression and effectively seals the space between the lid and the body. However, the compression necessary to obtain an adequate sealing of the chest causes a tension to be placed upon the hinges and other mechanical parts of 15 the chest.

20 A further desirable feature of chests and like articles is the provision of means for lifting the lid of the chest upon releasing the latch or lock holding the lid in closed position. Such a device may be for example a spring lid lift mechanism. The pressure of such devices against the lid of the chest likewise puts a considerable strain 25 on the hinge and tends to cause the leaves of the hinge to warp and to pull apart at the pivot line. Such a device also makes it very desirable to provide some means for stopping and supporting 30 the lid in open position.

35 One of the purposes of the present invention is to provide a hinge which will withstand the strains put upon it when installed in an aroma-tight chest without warping or pulling apart at the pivot line.

40 A further purpose of the invention is the provision of a hinge which will also act as a stop or a stay hinge.

45 Another purpose of the invention is to provide a cedar chest assembly in which the various parts cooperate to maintain a permanently aroma-tight chest which will also be easily accessible.

50 The invention will be more particularly described with reference to the accompanying drawings illustrating an embodiment of the invention.

In the drawings

55 Fig. 1 is a partial view of a chest assembly;

Figs. 2 and 3 are plan views of the hinge of the invention from the rear and the front of the chest, respectively; and

Figs. 4 and 5 are sectional elevations of the hinge shown in Figs. 2 and 3 in open and closed 5 positions, respectively.

In Fig. 1, 1 represents the back, 2 the side and 3 the lid of a chest. The lid is provided with resilient sealing strips 5 of metal or other resilient material, which in closed position of the 10 lid, contact with the top edge of the body.

A spring lid lift device 20 including a spring actuated arm 21 moving in track 22, more particularly described in application Serial No. 86,653 filed June 22, 1936, is also advantageously provided.

The hinge 8 of the invention in the embodiment shown in the drawings is mounted with one wing on the back side of the back of the chest and the other wing on the under side of 20 the lid. Other mountings may of course be used.

The hinge which is shown more fully in Figs. 2—5 comprises an upper or moving wing 10, a lower or stationary wing 11 and a pivot member 12. The lower or stationary wing comprises a web 13 portion 13 and side portion 14 forming a box section. The web portion of the wing is bent into the box section adjacent the pivoting end of the wing to form a stop ledge 15, while the corresponding ends of the side portions of the 30 wing are continued into ears 16 which are bored to receive pivot pin 12. The extreme edge 17 of stop ledge 15 is shaped to frictionally engage a portion of the movable wing as the hinge approaches the fully open position and thus provides a friction brake member which cushions the stopping action of the stop ledge, and holds the lid firmly in the open position so that a fairly substantial pull is required to start the closing movement, thus preventing closure of 40 the chest by means of accidental bumping or jarring.

The upper or movable wing has its end adjacent the pivot line formed into a box section. The main portion 18 of this box section forms a 45 stop ledge cooperating with the stop ledge 15 of the stationary wing, while the side portions 19 of the box section are bored similarly to ears 16 of the stationary wing to take pivot pin 12.

It will thus be seen that the new hinge embodies a number of advantages and that it cooperates with the other features of the chest assembly to provide an easily and safely handled aroma-tight chest construction.

The holding of the pivot pins, in extending at 55

right angles to the pivot line provides a strong construction capable of resisting the strain imposed upon the hinge by resilient sealing strips and the spring lid lifts without warping or 5 loosening.

The hinge also provides a lid stop and holding device which is very convenient in the use of chests and the like and which is particularly advantageous when the chest is provided with 10 a spring lid lift. It eliminates the use of a separate stopping device which would otherwise be necessary and which, in the forms usually provided is both inconvenient and unsightly.

The invention is not limited to the particular 15 form shown and described for the purpose of illustration but may be given a wide variety of shapes and arrangements without departing from the principles of the invention.

We claim:

20 1. A hinge comprising a pair of wings, each of said wings having a portion adjacent the pivot line extending perpendicularly to the major plane of the wing and parallel to the pivot line so as to abut in a predetermined open position of the 25 hinge to form a stop one of said extending portions being shaped to frictionally engage a portion of the other wing as it approaches the predetermined open position.

2. A hinge comprising a pair of wings each having a portion positioned to mutually abut in a predetermined open position of the hinge to form a stop and one of said abutting portions having an extension adapted to frictionally engage the other abutting portion as it approaches the predetermined open position.

3. A hinge comprising a pair of wings each having a portion positioned to mutually abut in a predetermined open position of the hinge to form a stop and one of said abutting portions 40 having a resilient extension adapted to frictionally engage the other abutting portion as it approaches the predetermined open position.

4. A hinge comprising a pair of wing members each having a ledge portion at one end thereof extending perpendicularly to the major plane of the wing and means for pivotally joining said wing members on a line parallel to and offset from both of said ledge portions, whereby said ledge portions abut to form a stop in a predetermined open 45 position of said hinge, one of said ledge portions being formed to frictionally engage the other ledge portion as it approaches the predetermined open position.

5. A hinge comprising a pair of wing members, 50 one wing member having a ledge at one end thereof extending rearwardly perpendicularly to the major plane of said wing, the other wing member having a ledge at one end thereof extending forwardly perpendicularly to the major 55 plane of the wing and means for pivotally joining said wing members on a line parallel to and offset from both of said ledge portions, whereby said ledge portions abut to form a stop in a predetermined open position of said hinge.

6. A hinge comprising a pair of wing members, 60 one wing member having a ledge at one end thereof extending rearwardly perpendicularly to the major plane of said wing, the other wing

member having a ledge at one end thereof extending forwardly perpendicularly to the major plane of the wing and means for pivotally joining said wing members on a line parallel to and offset from both of said ledge portions, whereby said 5 ledge portions abut to form a stop in a predetermined open position of said hinge, one of said ledge portions being formed to frictionally engage the other ledge portion as it approaches the predetermined open position.

7. A hinge comprising a pair of wing members, one wing member having a ledge portion at one end extending substantially perpendicularly to the major plane of the wing and spaced ears projecting beyond the plane of said ledge portion; 15 the other wing having one end disposed between and pivoted to said ears and also having a ledge portion extending substantially perpendicularly to the major plane of the wing and disposed between the pivot line and the ledge portion on said 20 first mentioned wing in the open position of said hinge so that said ledge portions abut to form a stop in a predetermined open position of said hinge.

8. A hinge comprising a pair of wing members, 25 one wing member having a ledge portion at one end extending substantially perpendicularly to the major plane of the wing and spaced ears projecting beyond the plane of said ledge portion; the other wing having one end disposed between and pivoted to said ears and also having a ledge portion extending substantially perpendicularly to the major plane of the wing and disposed between the pivot line and the ledge portion on said 30 first mentioned wing in the open position of said hinge so that said ledge portions abut to form a stop in a predetermined open position of said 35 hinge, one of said ledge portions being formed to frictionally engage the other ledge portion as it approaches the predetermined open position.

9. In a hinge, a wing having an inturned end flange and side portions providing ears adjacent said end flange, a second wing having inturned side flanges and an inturned end flange, the side flanges projecting longitudinally beyond the end 45 flange to provide spaced ears embracing the ears on said first mentioned wing and pivotally connected thereto, said end flanges being disposed on the same side of the pivot line, whereby said end flanges abut to form a stop in a predetermined 50 open position of said hinge.

10. In a hinge, a wing having an inturned end flange and side portions providing ears adjacent said end flange, a second wing having inturned side flanges and an inturned end flange, the side 55 flanges projecting longitudinally beyond the end flange to provide spaced ears embracing the ears on said first mentioned wing and pivotally connected thereto, said end flanges being disposed on the same side of the pivot line, whereby said end flanges abut to form a stop in a predetermined 60 open position of said hinge, one of said end flanges being formed with a resilient portion arranged to frictionally engage the other end flange as it approaches the predetermined open position.
